INVENTOR,

Dr. Chester A. Washburn

Harry W. Brown
ATTORNEY.

UNITED STATES PATENT OFFICE.

CHESTER A. WASHBURN, OF SPRINGFIELD, MASSACHUSETTS.

LEG REST.

Application filed October 17, 1921. Serial No. 508,195.

To all whom it may concern:

Be it known that I, CHESTER A. WASHBURN, M. D., a citizen of the United States of America, residing at Springfield, in the county of Hampden, Commonwealth of Massachusetts, have invented certain new and useful Improvements in Leg Rests, of which the following is a specification.

This invention relates to improvements in surgical appliances and it has for one of its objects to provide a device that can readily be carried from place to place as required.

A further object is to provide a device that is particularly designed for supporting a foot or limb of a patient while being treated or the surgical bandages are being applied or removed.

A further object is to provide a device that can be readily adjusted in order to make the patient as comfortable as possible.

A further object is to provide a combined cabinet and surgical appliance for the purpose of having a convenient receptacle for storing the necessary implements and medicines and the usual materials that are necessary for such work.

A further object is to provide means whereby the appliance can be readily folded into a compact or small compass.

A further object is to provide a suitable basin or receptacle for receiving or catching any liquids or pieces of bandages that may occur during the use of the appliance.

Referring to the drawings:

Fig. 1 is a general side elevational view showing the stirrup device, the vertical adjusting device therefor, the dotted line showing the folded positions of the stirrups, also the drawer and the shelf.

Fig. 2 is the vertical sectional view on the line 2—2 of Fig. 1 showing one of the stirrups in open position also the shelf, the basin or pan and the drawer for receiving the supplies.

Fig. 3 is an enlarged detail view of one of the stirrups showing the expansion spring for holding the arms of the stirrups in either an open or closed position also the movable bar for receiving the ends of the fabric which composes the stirrups.

Fig. 4 is a detail view on the line 4—4 of Fig. 3 showing one of the stirrup arms having the radial recess to receive the projections on the other arm.

Fig. 5 is a detail view on the line 5—5 of

Fig. 3 showing the arms folded and the fabric depending between the folded arms also showing the shaft in section, in which the arms are pivotally rotated.

Fig. 6 is a view showing means for adjusting the length of the stirrup, and

Fig. 7 is a view showing means for retaining the stirrup holding roller in different positions of adjustment.

Referring to the drawings in detail:

1, 2, and 3 designate the frame which supports the appliance and is preferably formed on angle iron. The legs 1 which are provided with a pad or cushion at their lower ends to prevent the appliance from slipping as indicated at 4, while the legs 2 are provided with rollers 5 whereby when the appliance is to be moved it is only necessary to elevate one end and roll it along the floor. 6 designates a basin or receptacle which is supported by means of the flange 7 engaging the upper ends 8 of the legs as shown in Fig. 2. Slidably mounted in the frame is the drawer 9 which is supported on the cross bars 10. This drawer is for receiving any of the usual materials which a surgeon uses in dressing wounds or any other of the necessary surgical implements. 11 designates sockets mounted on the sides of the legs of the frame work for receiving the brackets 12 which supports a swinging shelf. These brackets permit the user to place thereon the implements or other articles which are being used.

Referring now more in detail to the stirrup construction which supports the limb or foot of the patient, 13 and 14 designate sockets that are attached to the opposite ends of the framework and in these sockets are located the sliding rods 15 and 16. 17 are thumb nuts for holding the rods 15 and 16 in different positions of adjustment. The rod 15 is further provided with a bolt 18 and a thumb nut 19. Slidably supported on the rod 15, is the upwardly extended curved arm 20 having a slot 21 which slot receives the bolt 18 and therefore permits this arm to be raised or lowered and adjusted or held in any suitable position or height. Attached to the arm 20 is a rod 21' by means of a pin 105 22. This rod is rectangular in cross section, as shown in Fig. 5. 23 designates a second arm at the opposite end of the appliance which is pivotally connected to the rod 16 at 24. The pivot 24 therefore permits the arm 110

105 22. This rod is rectangular in cross section, as shown in Fig. 5. 23 designates a second arm at the opposite end of the appliance which is pivotally connected to the rod 16 at 24. The pivot 24 therefore permits the arm 110

20 and rod 21' to be raised or lower since it would swing about this point as a center. Secured to the upper end of the arm 23 is a tubular member into which the rod 21' telescopes. 26 and 27 designate as a whole the two stirrups which support the limb of the patient. These stirrups are formed of four arms 28, 29, 30 and 31. The arms 28 and 29 are spaced from the arms 30 and 31 along 5 the rods 21' and 25. The lower ends are formed with enlargements and disk shaped plates 32. 28' and 31' are plates to prevent the outward movement of the arms of the stirrups. One of these is formed with projections 33 which engages correspondingly shaped recesses 34 in the oppositely located plate. 35 designates a fixed flange on the tubular member 25 and against which the arm 31 bears. For the purpose of forcing 10 the arms 28 and 29 outward and the arms 30 and 31 against the flange or stop 35 a coiled expansion spring 36 is located between these pairs of arms as shown in Fig. 3 whereby the two pairs of arms are frictionally held in different positions of adjustment but at the same time permits them to be swung either into an open or closed position as indicated in Figs. 2 and 5 by reason of the ribs 33 engaging the recess 34. Engaging 15 the upper ends of the two pairs of arms and connecting the same are the swinging bars 37. These bars are for the purpose of receiving the loops in the fabric or band 38. They are made to swing as shown in Fig. 3 whereby the fabric may be put on or taken off as desired and also to permit the arms to be folded in opposite directions indicated by the arrows 39 in Figs. 2 and 5. The two pairs of arms which constitute the 20 stirrups may be folded as a whole into the dotted line position indicated in Fig. 1. The stirrup 26 may be slid or moved along the rod 21' to accommodate the patient which is being treated as indicated by the arrows 40. The stirrup 27 is constructed in the same manner as that already described in connection with stirrup 26 and may be folded into the dotted line position indicated at 41. It is of course obvious that the stirrup 27 may be located at different longitudinal 25 positions along the tubular member 25 but is preferably shown and used in the position indicated against the upwardly extended bar 23. A coiled expansion spring 42 is used for the same purpose as the spring 36. For the purpose of protecting the springs 36 and 42 a tube 43 is used. This tube also serves as a spacer or limit device for the two pairs of arms which constitute 30 the stirrup. The center part of the tubular member 25 indicated at 25' serves as the handle by means of which the appliance may be carried by the user when desired from place to place.

65 It is to be understood that the applicant

does not limit his appliance to any particular size of parts or material as it may be made portable or otherwise.

It is also to be understood that the stirrup members 38 are so constructed that they 70 may be readily changed for sanitary purposes or reasons as for example, by forming loops at their ends to slip over the rods 37.

Referring to Fig. 6 44 and 45 indicate tubular rods for receiving and retaining the 75 stirrup fabrics or bands 46. The rod 44 is provided with a slot 44'. In the slot 44' is placed one end of the fabric and the hemmed end 46' prevents the fabric from pulling through. 47 designates a swinging 80 device which is pivoted to the arm 31 at 47' and is provided with a cross bar 47' formed with teeth 47' which engage the fabric for clamping the free end whereby the length between the rods 44 and 45 may be adjusted 85 to the comfort of the wearer. When weight is applied to the center portion of the fabric 46 the teeth 47' of the bar 47' will pinch the fabric between it and the tube 45. To release and adjust, it is only necessary to pull 90 downward on the free end 46'.

In Fig. 7 the rod 45 may be mounted for rotation in bearings 48 for winding the free end of the fabric 46 thereon. It is held in different positions by means of the pin 49 95 which passes through the openings 50 and 51 in the bearing 48 and the end portion 49. By means of the construction shown in Figs. 6 and 7 the comfort of the user may be accomplished.

100 What I claim is:

1. A surgical appliance for the purpose described, the combination, of a rigidly constructed frame work constituting the supporting base, a pair of stirrup members located above the same, means for varying the vertical and inclined adjustment of said members said means including telescoping supporting bars adjustably secured to the ends of the supporting base, and means for retaining said members in their adjusted 105 positions.

2. In a surgical appliance, the combination with a supporting base, of socket devices located at the ends of the same, slidably mounted rods in said sockets, means for securing the rods in the sockets, one of the rods having a pivotal joint at its upper end, a bar formed with a slot for receiving one of the rods, whereby the same may be held 110 in different positions of adjustment on the upper end of the slidably mounted rod, a bar pivotally attached to the slidably mounted bar, a rod connecting the two last mentioned bars, stirrups mounted on the rod, 115 whereby the vertical and angular position of the stirrups may be varied as described.

3. A stirrup device for the purpose described comprising two pairs of arms, means for retaining the arms in different angular 120 125 130 positions.

positions of adjustment, the upper ends of the pairs of arms being connected by swinging bars, said bars being for the purpose of receiving the fabric or other flexible member for supporting the foot or limb of the patient said pairs of arms being so mounted as to permit the entire stirrup to be swung or rotated about its support.

4. A stirrup for the purpose described, comprising two pairs of arms, means for pivotally and slidably mounting the same on a suitable rod, an expansion spring on the rod for forcing the pairs of arms outwardly, the opposite faces of the arms being formed with serrations and depressions, respectively, whereby the arms may be located in different angular positions of adjustment relative to each other, and a fabric or stirrup connecting the upper ends of the arms for supporting the limb or foot of the patient and means for supporting the rod.

5. In a surgical appliance, the combination, of a rigidly constructed frame work constituting the supporting base, two stirrups, a rod for supporting the stirrups, means for attaching the rod to the opposite ends of the supporting base, said means permitting the elevation of the ends of the rod and stirrups thereon to be varied for locating the stirrups at different elevations with relation to each other.

6. In a surgical appliance, the combination of a pair of stirrups, a rod for supporting the same, a base or frame work, and slidable means for connecting the ends of the rod to the base to permit the rod to be moved into different inclined positions for varying the vertical positions of the stirrups.

7. In a surgical appliance, the combination of a pair of stirrups, a rod for supporting the same, a base or frame work, means for connecting the rod to the base to per-

mit the rod to be moved into different inclined positions, said means including two adjustable bars on the base, pivotal connection at one end of the rod with one bar and a slidable connection at its other end with the other bar. 45

8. In a surgical appliance, the combination, of a plurality of spaced swinging stirrup members, fabrics thereon and extending from the free ends of the members, means for adjusting the length or depression of the fabrics between its ends, a rod for supporting the stirrup members, a base or frame work for supporting the rod, and means for slidably connecting the ends of the rod to the framework to permit the rod to be moved into different inclined positions of adjustment for varying vertical heights of 60 the said members. 55

9. In a leg rest structure, stirrup devices each including two pairs of laterally swinging arm members, a leg supporting fabric thereon, and means for varying the length 65 of the leg supporting fabric.

10. A leg rest comprising two pairs of swinging arms, a single rod for supporting the two pairs of arms, a flexible leg supporting member attached to the arms, means for varying the length of the flexible member including two tubes with a slot in one tube to receive one end of the flexible member and a device for clamping the flexible member to the other tube. 75

11. A leg rest structure having a plurality of spaced stirrup members telescopic rods for supporting the same, means for adjusting the rods in different inclined positions, said stirrup members including flexible devices for supporting the leg, and means for adjusting the length of the flexible devices. 80

CHESTER A. WASHBURN, M. D.
